The ornamental design for a mammogram and radiation gown, as shown and described.

DESCRIPTION

FIG. 1 is a front view of the mammogram and radiation gown design of the present invention showing the front of the gown completely closed;

FIG. 2 is a front view thereof showing the front of the gown partially opened;

FIG. 3 is a front view thereof showing the front of the gown substantially completely opened;

FIG. 4 is a rear view thereof showing the rear of the gown completely closed;

FIG. 5 is a rear view thereof showing the rear of the gown partially opened; and,

FIG. 6 is a rear view thereof showing the rear of the gown substantially completely opened.

The broken lines in FIGS. 1-6 represent stitching.
